ELECTROMAGNETIC DEVICE

Emil Dickten, Jr., Totowa, N. J., assignor to Bell Telephone Laboratories, Incorporated, New York, N. Y., a corporation of New York

Application July 11, 1940, Serial No. 344,900

2 Claims. (Cl. 175—339)

This invention relates to electromagnetic devices and more particularly to devices which are polarized to be responsive to current of but one polarity.

The object of the invention is to enable the modification of neutral relays or electromagnetic devices in a simple manner to render them selectively responsive to energizing current of a predetermined polarity.

This object is attained by bridging a portion 10 of the magnetic circuit of an electromagnetic device by a permanent magnet thereby forming a magnetic rectifier which admits the flow of magnetic flux to enable the device to operate when energizing current of a predetermined polarity is applied to the operating coil of such device and which impedes the flow of magnetic flux to prevent the operation of the device when energizing current of the opposite polarity is applied to the operating coil. In accordance with 15 the invention the permanent magnet bridge may be applied around the operating coil between the opposite ends of the core, may be applied between the forward end of the core and the return pole-piece, or may be bridged around a portion of the core.

For a more comprehensive understanding of the invention reference may be had to the following detailed description taken in connection with the accompanying drawing in which:

Fig. 1 is a top plan view of a neutral relay modified in accordance with the present invention;

Fig. 2 is an end view of the relay disclosed in Fig. 1;

Fig. 3 is a perspective view, partly in cross-section, of a message register modified in accordance with the present invention;

Fig. 4 shows one of the permanent magnet supporting details of Fig. 3;

Fig. 5 shows a core for an electromagnetic device modified in accordance with the present invention;

Fig. 6 shows the core of Fig. 5 partly in cross-section to better disclose the construction thereof; and

Fig. 7 is a circuit illustrative of one application of the invention.

Referring first to Figs. 1 and 2 the invention has been illustrated as applied to a well-known 50 type of neutral relay. It is to be understood, however, that while a particular type of relay is disclosed, neutral relays of other types could be modified in the same manner to function as unidirectional or polarized relays.

The relay of Figs. 1 and 2 has a core 1, the rear end of which is widened to form a heel-piece 2 and is bifurcated to form two sections bent in opposite directions to provide mounting ears 3 and 4 by which the relay may be attached to a mounting plate, and the forward end of which core is provided with a pole face 5. Mounted on the core is an energizing coil 6 having a rear spoolhead 7 and a forward spoolhead 8. The U-shaped armature 9 is positioned with its forward cross-reach 10 overlying the pole face 5 of the core and its side arms extending on either side of the coil 6 with their ends pivoted to the forward edge of the heel-piece 2 by reed springs 11. The cross-reach 10 of the armature is normally biased against the back-stop nut 12 which is threaded upon one end of stud 13 secured in a hole in the end of core 1. The back-stop nut 12 serves as a means for limiting the releasing movement of the armature and for adjusting the length of the air-gap between the cross-reach 10 of the armature and pole face 5 of the core 1.

Insulatedly mounted on each end of the heel-piece 2 is a spring pile-up, each pile-up comprising as many contact springs as may be required but as shown comprising springs 14, 15, 16 and 17 and a coil terminal lug 18. The springs and terminal lug of each pile-up are clamped to the heel-piece 2 between the clamping plates 19 and 20 by screws 21 which extend through aligned holes in the plate 19, spring 14, lug 18, heel-piece 2, reed spring 11, springs 15, 16 and 17 and through holes in insulation strips which insulate such springs and lugs from each other, from the heel-piece 2 and from the clamping plates 19 and 20, and into threaded holes in the clamping plate 20. The spring 15 of each pile-up engages an insulating stud 22 carried by the armature 9 whereby the springs 15 serve to normally bias the armature against the back-stop nut 12. The attraction of the armature toward the core through the studs 22 moves springs 15, 16 and 17 of each pile-up into engagement and moves spring 15 of each pile-up out of engagement with the associated spring 14.

For rendering the relay unidirectional or polarized in operation, a permanent bar magnet 23 is positioned parallel to the core 1 and bridged to the core around the outside of the coil 6 by spacing blocks 24 and 25 of magnetic material. The block 24 is seated on the forward end of the core 1 and the block 25 is seated on the heel-piece 2 and each block is provided with grooves in the edges thereof. For securing the magnet 23 to the core 1 screws 26 are provided which

extend through holes in the clamping plate 27 on either side of the magnet 23, lie in the grooves in the edges of the blocks 24 and 25 and enter threaded holes in the core 1 and heel-piece 2 of the core. The poles of the permanent magnet are thus magnetically connected to the ends of the core and the magnet is bridged around that portion of the core on which the coil 6 is supported. With the permanent magnet thus connected a flow of flux is set up in the core 1 which may be visualized as leaving the north pole of the magnet, entering the heel-piece 2 through block 25, flowing forwardly through the core 1 and entering the south pole of the magnet through block 24 thereby substantially saturating the core 1.

If current of a predetermined polarity is now applied to the coil 6, a coil flux will be set up in the core 1 which will flow rearwardly through the core, returning through the side arms of the armature 9 and the cross-reach 10 thereof, across the air-gap to the forward end of the core. The coil flux will therefore oppose the permanent magnet flux in the core 1 and the flux density in the core is therefore decreased whereby flux readily flows across the air-gap between the cross-reach 10 and the end of the core 1 whereupon the armature 9 becomes attracted to operate the springs of the spring pile-ups.

If current of the opposite polarity is applied to the coil 6, a coil flux will be set up in the core 1 which will tend to flow forwardly through the core 1 and thus aid the permanent magnet flux, but, since the core 1 is almost or entirely saturated due to the flux from the permanent magnet, the increase in flux in the core will be slight or nil and practically no flux will flow across the air-gap between the armature and the forward end of the core and therefore the armature will be unaffected.

Fig. 3 illustrates the application of the invention to an electromagnetic device, for example, to a subscriber's message register of well-known construction. The register is provided with a U-shaped return pole-piece 28 having legs 29 and 30 and to the base of which a core is secured which extends forwardly between the legs 29 and 30. The core is provided with a rear threaded portion 31 which extends through a hole in the base of the return pole-piece and upon which a nut 32 is threaded for clamping the core to the pole-piece. Mounted upon the core is an operating coil 33 having rear and forward spoolheads 34 and 35. Supported on the core between the rear spoolhead 34 and the base of the return pole-piece is a rear permanent magnet support 36 and supported on the forward end of the core beyond the front spoolhead 35 is a front permanent magnet support 37. These supports are of magnetic material and each is, as most clearly shown in Fig. 4, provided with a central opening 38 through which the core extends and with a recessed portion 39 in its upper edge of sufficient extent to receive the end of a permanent bar magnet 40.

An armature (not shown) is pivoted between the forward ends of the legs 29 and 30 of the return pole-piece for cooperation with the forward end of the core and the forward ends of the legs 29 and 30 are held in spaced relationship to each other and to the forward end of the core by a plate 42 of non-magnetic material secured to the legs 29 and 30 by screws 41. A mounting member 43 for the message register mechanism is also secured to the forward ends 75

of the legs 29 and 30 by the screws 44, such mechanism being positioned beneath the dust cover 45.

Due to the bridging of the ends of the core 5 through the supports 36 and 37 and through the permanent magnet 40 the message register armature will be attracted towards the forward end of the core in the manner previously described in connection with the relay of Fig. 2, only when 10 current of a predetermined polarity is applied to the coil 33.

The bridging effect may also be accomplished in the core itself as illustrated in Figs. 5 and 6 by fabricating the core in three sections. The 15 rear section of the core 49 is provided with a reduced threaded portion 50 by means of which the core assembly may be secured to the return pole-piece and has an axially formed socket 51 in its forward end. The forward section 52 of 20 the core is provided with a shouldered portion 53 adjacent its forward end and with a shouldered portion 54 on its rear end which may be inserted in the socket 51 of the rear core section 49 as disclosed in Fig. 6. The shank 55 of the forward core section 52 of the core between the shouldered portions 53 and 54 is reduced in diameter. Supported on the shouldered portions 53 and 54 of the forward core section is a tubular permanent magnet 56. In order that the three 25 sections of the core may be held in their assembled position, the shouldered portions 53 and 54 are of such a diameter that they have a driving fit in the tubular magnet 56 and in the socket 51 of the rear section. It will be noted that due to 30 the reduced diameter of the shank 55 the permanent magnet engages the core sections 49 and 52 only at its polar ends and that it therefore constitutes a bridge of the shank 55, so that the shank is normally almost or entirely saturated 35 by the flux from the permanent magnet which may be visualized as leaving the north pole of the magnet, entering the shouldered portion 54, flowing through the shank 55 and entering the south pole of the magnet through the shouldered portion 53. The core structure disclosed in Figs. 40 5 and 6 may be employed to replace the usual core of an electromagnetic device, such as a message register of the type shown in Fig. 3, for rendering such device responsive to current of a 45 predetermined polarity, no other change in the 50 structure of the device being necessary.

If it is desired to render the electromagnetic devices illustrated responsive to operating current of the opposite polarity all that is required 55 is to reverse the connection of the coil terminals to the operating circuit. For example, if two such identical devices are connected in series in an operating circuit and the coils are reversely connected one device will operate on current of one polarity and the other device will operate on current of the reverse polarity.

As illustrative of one application of a polarized electromagnetic device of the type illustrated, for example, in Fig. 3, Fig. 7 shows a 60 two-party telephone line having substations 57 and 58 thereon, terminating in the bank of a line finder 59. The line is equipped with the usual line relay 60 which is operable upon the initiation of a call from either substation of the line to cause an idle line finder to connect with the line, and with the usual cut-off relay 61 which is operable when the calling line has been seized by a line finder to open the operating circuit of the line relay 60. For metering calls initiated by either substation 57 or 58 two serially

connected message registers 62 and 63 of the type disclosed in Fig. 3 or as modified in accordance with Figs. 5 and 6 may be employed. Register 62 is allocated to substation 57 and register 63 is allocated to substation 58 and such registers are oppositely polarized.

Should the party line subscriber at substation 57 initiate a call, the metering switch 64 will at the appropriate time be so operated as to connect the negatively poled battery 65 in a circuit over metering brush 67 of line finder 59, bank terminal 68, back contact of relay 69, thence through the windings of message register magnets 62 and 63 to ground whereby only register 62 will be operated. Should the party line subscriber at substation 58 initiate a call, the metering switch 64 will at the appropriate time be so operated as to connect the positively poled battery 66 into the previously traced metering circuit whereby only register 63 will be operated.

What is claimed is:

1. In an electromagnetic structure, a core of magnetic material, an operating coil thereon and an armature cooperating with said core, said core comprising a continuous intermediate portion of reduced diameter provided with flanged ends and

5 a tubular permanent magnet surrounding said portion with only its polar ends in engagement with the flanged ends of said reduced portion thereby bridging that portion of said core, the coil located to surround the said intermediate portion and magnet whereby said armature is attracted toward said core only when said coil is energized by current of a predetermined polarity.

2. In an electromagnetic structure, a core, an operating coil thereon and an armature cooperating with said core, said core comprising a rear section having a socket in the outer end thereof, a front section having a rearwardly extending shank portion the rear end of which is seated in said socket, said shank being reduced in diameter throughout the major portion of its length and a tubular permanent magnet supported on said shank portion between said rear and front sections with only its polar ends in engagement with said rear and front sections thereby bridging said shank portion, whereby said armature is attracted towards said core only when said coil is energized by current of a predetermined polarity.
